UNITED STATES PATENT OFFICE.

ALBERT CHAMPION AND ALBERT SCHMIDT, OF FLINT, MICHIGAN, ASSIGNEES TO
CHAMPION IGNITION COMPANY, OF FLINT, MICHIGAN, A CORPORATION OF MICHIGAN.

SPARK PLUG.

Application filed September 25, 1918. Serial No. 255,581.

To all whom it may concern:

Be it known that we, ALBERT CHAMPION and ALBERT SCHMIDT, citizens of the United States, both residents of Flint, Genesee County, State of Michigan, have invented certain new and useful Improvements in Spark Plugs, of which the following is a specification.

The invention relates to improvements in spark plugs as described in the present specification and illustrated in the accompanying drawing that forms part thereof.

One of the objects of the invention is to devise a spark plug of simple and durable construction.

Another object of the invention is to devise a spark plug in which the insulator may be firmly seated in the shell during assembly without liability of fracture.

Another object of the invention is to devise a spark plug in which the sealing of the joints between the insulator and shell may be most effectively made.

Another object of the invention is to devise a spark plug in which the means for clamping the insulator within the shell will distribute the pressure thereof over the greatest possible area of the insulator in an even manner, whereby maximum strength of assembly arrangement is secured.

These and other objects will more clearly appear from the following description taken in connection with the accompanying drawings which form a part of the same.

Referring to the drawings, Figure 1 is a vertical sectional view of a preferred form of our invention. Figure 2 is a vertical sectional view of a modified form of our invention. Figure 3 is a vertical sectional view of a further modified form of our invention.

Like numerals of reference indicate similar parts throughout the views.

Referring to the drawings and particularly Fig. 1, 10 is the shell of a spark plug made of any desired form on the exterior thereof and having the interior bore 11 with the flange 12 on which the insulator 13 supporting the central electrode 14 is arranged as well known in the state of the art.

The insulator 13 comprises the body portion 15 and the upwardly extending neck portion 16, the body portion gradually re-

ducing to the neck portion in stepped form as at 17.

The stepped portion of the insulator is covered with a coating of suitable varnish, "bakelite" or other suitable material to form a very thin gasket, and a collar 18 of hard metal is seated upon said gasket within the bore of the shell, the exterior periphery of the collar fitting the bore of the shell and the interior periphery of the collar conforming to the contour of the stepped portion of the insulator.

The assembly of the spark plug is completed by turning over the top flange 19 of the shell onto the collar 18, the flange pressing the collar firmly down onto the stepped portion of the insulator with an even and well distributed pressure and bearing surface, whereby the insulator is properly and firmly pressed downwardly and seated on a gasket 20 on the flange 12 of the shell.

It must be understood that the advantage of evenly distributing the pressure over a large area is of very great importance, but in addition thereto should any possible leak occur past the gasket 20, such leak will be of no avail as the sealed collar at the top of the shell will further effectually prevent the passage of any gas and consequent heating of the upper portion of the plug.

It must be understood that though we have shown the collar as fastened by turning in the upper flange of the shell, any suitable means such as screwing in a second collar to a correspondingly threaded portion of the shell may be employed for the purpose.

Referring particularly to the modification shown in Fig. 2, the shell 10 is shown with the upper end thereof enlarged and threaded as at 21, and the neck of the insulator 13 is shown to be of regular curved formation as at 22. This portion of the insulator is coated with material as described with reference to the form shown in Fig. 1, and a collar 23 conforming to the shape of the insulator is placed thereon and firmly pressed with the insulator into seated position in the shell by the threaded collar or nut 24, screwed into the correspondingly threaded part 21 of the shell, as well understood.

In the modification shown in Fig. 3, the gasket 25 is of comparatively thick material

and the collar 26 is of comparatively small cross section compared with those described, and it must be here explained that the sizes and proportions of both the gasket and the 5 collar may vary quite widely, always providing the essential feature is maintained, that is, the collar must be of such form and material as will not distort when the pressure of assembly is brought upon it, and thus 10 the collar will receive the direct pressure of either a clamping means, such as the turning in of the top flange of the shell, or the pressure of a collar or other member screwed into the upper end of the shell, and will 15 evenly distribute such pressure through the gasket to the insulating member, which is of fracturable material and therefore to be carefully guarded.

It must also be understood that any suitable 20 material may be used in place of the gasket of varnish or other suitable material referred to, and in fact, it may readily occur that the gasket at the lower seat of the insulator may be quite sufficient for sealing 25 purposes and the gasket at the upper part of the insulator may be eliminated entirely, the finished interior contour of the collar and the correspondingly finished exterior contour of the insulator about the 30 neck thereof being quite sufficient to evenly distribute the pressure thereabout without causing danger of fracture.

It will be obvious to those skilled in the art that many modifications and changes 35 may be made without departing from the spirit and scope of the invention.

Having now described our invention what

we claim as new and desire to secure by Letters Patent is:

1. In a spark plug, an external shell or 40 casing having an interior bore, and a supporting flange at the lower end of said bore; an insulator member located within said bore and having an enlarged central portion the lower end of which is supported by said 45 flange, and the upper end of which is provided with a series of shoulders of different diameters; an annular collar located within said interior bore and above the upper end of the enlarged central portion aforesaid 50 of said insulator, and which collar is provided with a series of internal shoulders adapted to engage the shoulders aforesaid at the upper end of the central portion of said insulator; and a top flange integral 55 with said shell or casing and extending inwardly and over the upper end of said annular collar to thereby hold the same in place within said interior bore.

2. A spark plug comprising a shell, an 60 insulator seated in said shell and having a body portion and an upwardly extending neck portion formed at the base thereof in stepped formation, a gasket of thin flexible material fitting on said insulator at the 65 juncture of the body and neck portions, a collar of definite shape and corresponding to the contour of the insulator and seating on said gasket, and means engaging said collar to seat said insulator.

In testimony whereof, we affix our signatures.

ALBERT CHAMPION.
ALBERT SCHMIDT.
